UNITED STATES PATENT OFFICE.

CARL WEBER, OF CHICAGO, ILLINOIS.

METHOD OF PLASTERING WALL-SURFACES.

1,139,091.

Specification of Letters Patent. Patented May 11, 1915.

Application filed February 12, 1914; Serial No. 818,380. Renewed March 29, 1915. Serial No. 17,887.

To all whom it may concern:

Be it known that I, CARL WEBER, a citizen of the United States, residing at Chicago, in the county of Cook and State of Illinois, have invented a new and useful Improvement in Methods of Plastering Wall-Surfaces, of which the following is a specification.

My invention relates to an improvement in the art of plastering wall-surfaces by impelling the material against the surfaces through the medium of air-pressure. Two systems of thus applying plaster are known to me as being in more or less extensive use. Each employs a machine for impelling the mixture of materials (as cement and sand) by air-pressure through a nozzle-tipped flexible hose, one for operating by what is known as the "wet" process and the other by what is known as the "dry" process. By the wet process all the water used for hydrating the cementitious material is supplied thereto in a hopper or closed tank, and the material is thereby reduced to a consistency to adapt it to flow readily through pipes; but the large quantity of water thus added renders the plaster porous and thus impairs it for its purpose. On the other hand, if the quantity of added water be relatively small, the material tends to clog the pipes and produce costly delays. By the dry process, the material formed of the mixture is blown in the condition of a dry powder through the hose and all the water is added to it within the nozzle. The practice of the method in this way is attended with various troubles, as the more serious among which may be mentioned that the cementitious portion of the material fails to adhere to the remainder or aggregate thereof while under propulsion and leaves the nozzle in a finely separated condition, and that supplying the water only in the nozzle fails to thoroughly moisten all particles of the material, because the distance between the nozzle and point of application of the plaster is too short for thorough action of the water to take place therein, and, moreover, a great loss ensues from dusting.

The object of my invention is to avoid the objections in both systems referred to.

For the practice of my improved method, a suitable machine is shown in the accompanying drawing by a broken view in sectional side elevation.

A hopper 1 surmounts and opens into a

neck 2 terminating at its lower end in a horizontally-extending nipple 3 to which is coupled a flexible hose 4 carrying on its distal end a nozzle 5 provided about its extremity with an annular chamber 6 having discharge-openings 6^a converging toward the nozzle-exit. A water-conducting hose 7 secured to the hose 4 to extend along it leads to the chamber 6 from a source of supply (not shown). In the upper part of the neck 2 is a cylindrical chamber 2^a containing a rotary valve 8 centrally journaled in the chamber and which may be rotated by hand or other power. The valve is formed of a central diaphragm extending diametrically across the chamber and having arc-shaped walls extending in opposite directions from its ends to form chambers 8^c and 8^d provided, respectively, with openings 8^e and 8^f to communicate alternately with the hopper and the neck below the chamber. A nozzle 9 connected with a source (not shown) of air under pressure, leads through the back of the neck in line with the inlet-end of the coupling of the hose 4. Immediately below the chamber 2^a a spraying ring 10 is provided in the neck, being let into the wall thereof, and has a pipe-connection 11 with a source (not shown) of water or other liquid or wet-steam supply.

To operate the machine thus described, the material (such as a mixture of cement and sand) is filled into the hopper, thereby filling the valve-chamber 8^c or 8^d, whichever is open to the hopper. Upon then turning the valve half-way about the other chamber will be filled from the hopper and the first-named chamber will empty its contents into the lower part of the neck. While the machine is being operated, air or other fluid under pressure is constantly admitted into the neck through the nozzle 9, and water is forced through the pipe 7 into the annular chamber 6. Only sufficient water is added to the material, either in or before it enters the hopper, or from the spray-ring 10 in the discharge of the material from a valve-chamber, to thoroughly envelop the solid particles of the material with a film of water, so that the cement and sand will better cohere while undergoing propulsion, and start hydration of the cement. The material in dropping from the valve enters the path of pressure from the nozzle 9 and is blown through the hose 4 and nozzle 5. The small quantity of water used for start-

ing hydration, as stated, facilitates the movement of the plaster-mixture under the impelling pressure, and requires consumption of a minimum quantity thereof, since 5 it reduces the skin-friction in the hose. When the material thus blown reaches the discharge-end of the nozzle 5, additional water from the openings 6^a mixes with it and readily unites therewith because of its 10 preparatorily moistened condition, and forms the plaster in a proper state for application to a wall-surface.

The spray-ring may be used either for the water-adding purpose stated, or for mixing 15 oil or coloring matter to the material; and it may be used to supply steam in cold weather to prevent freezing in the practice of the process.

As will be observed, the valve 8 in any 20 position affords an air-lock against the escape of fluid-pressure past it from the nozzle 9; and the valve-chambers receive and discharge the material in measured quantity, thereby conduced to uniformity 25 in the plaster-product.

From the foregoing description of my improved method, it will be apparent that it prevents all loss by dusting; that the pre- 30 paratorily moistened cement and sand will cohere in motion with sufficient tenacity to resist separation under the force of the air-pressure, and will, by reason of the moistened condition, take the added water readily and thus result in a uniform quality of 35 plaster; that it eliminates all danger of the material clogging the passages, and avoids the need of using for that purpose an excessive quantity of water in the material, 40 which would tend to impair the proper density and impermeability of the plaster; and that it effects economy in the use of impelling air-pressure.

What I claim as new and desire to secure by Letters Patent is:—

1. The method of applying plaster to 45 wall-surfaces, which consists in passing the cement and sand ingredients, in a condition of being only sufficiently moistened to cohere and start hydration of the cement, into the path of fluid-pressure currents, impelling the mixture by said pressure to the point of delivery to a wall-surface, and introducing the remaining water necessary to produce complete hydration into the previously moistened mixture near said point. 55

2. The method of applying plaster to 60 wall-surfaces, which consists in passing the cement and sand ingredients, in measured quantity and in a condition of being only sufficiently moistened to cohere and start 65 hydration of the cement, into the path of the fluid-pressure currents, impelling the measured and moistened mixture by said pressure to the point of delivery to a wall-surface, and introducing the remaining 70 water necessary to produce complete hydration into said mixture near said point.

3. The method of applying plaster to 75 wall-surfaces, which consists in passing the cement and sand ingredients into the path of fluid-pressure currents, introducing into the mixture on its approach to said path only sufficient water to produce cohesion of the particles of the ingredients and start hydration of the cement, impelling the moistened mixture by said pressure to the point of delivery to a wall-surface, and introducing the remaining water necessary to produce complete hydration into said mixture near said point.

CARL WEBER.
